UNITED STATES PATENT OFFICE.

ALFRED HERZ, OF CHICAGO, ILLINOIS, ASSIGNOR OF ONE-HALF TO EDMUND O. SCHWEITZER, OF CHICAGO, ILLINOIS.

FUSED CUT-OUT.

1,380,556.

Specification of Letters Patent. Patented June 7, 1921.

Application filed August 10, 1917. Serial No. 185,597.

To all whom it may concern:

Be it known that I, ALFRED HERZ, a citizen of the United States, residing at Chicago, in the county of Cook and State of Illinois, have invented a certain new and useful Improvement in Fused Cut-Outs, of which the following is a full, clear, concise, and exact description, reference being had to the accompanying drawings, forming a part of this specification.

My invention relates to fused cut-outs and the like.

In Patents Nos. 1,033,123 and 1,144,732 granted to Edmund O. Schweitzer and myself jointly, and in Patent No. 1,222,952 granted to me solely, there are described successive steps of the development of a form of fused cut-out which employs a fuse, and compression blocks upon opposite sides 20 of the fuse. These blocks are forced in by springs when the fuse softens and tend to smother and to chill or even prevent the arc which tends to form.

The present invention is a further improvement on that type of fused cut-outs.

I have employed in practice the structures described and claimed in the above patents up to substantially their limits of capacity. I have found that within the limits for 30 which they are designed they are efficient and reliable but in order to obtain greater capacity for interrupting current flow I have found it necessary to introduce certain novel structures and principles for 35 overcoming the greater liberation of energy. As the heat of the melting fuse or arc is roughly proportional to RI^2 , it will be appreciated that the energy to be dissipated increases on the order of the square 40 of the current to be interrupted, consequently a mere increase in size of the parts of the cut-out very quickly fails to keep pace with the requirements of increased current interrupting capacity.

I employ a novel principle of arc extinguishing as will be apparent from the following.

I provide compression blocks on opposite sides of the fuse and submerge the fuse and 50 blocks in oil. The compression blocks are spring pressed against two sides of the fuse and thus tend to choke off or even prevent

formation of the arc as soon as the fuse softens. The oil fills the space along the sides of the fuse and fills the space between the overhanging sides of the blocks. The oil prevents the escape of vapors which might be sufficiently conductive to re-establish an arc outside of the blocks; this is especially desirable in view of the high voltage of the circuits to which this form of device is adapted.

According to my invention I provide a motion-limiting device for the blocks to limit the outward movement of these blocks when the fuse blows. This tends to throw the force of the fuse explosion upon the body of oil. Unless the oil can also be limited in movement or forced in to choke off the arc, the arc may blow out sidewise and establish itself under the oil in the manner in which a plain fuse in oil operates. I provide means for creating a pressure of the oil. The particular means I employ is a tight casing about the entire device which is nearly filled with oil. When the fuse blows it automatically increases the pressure of the oil. These two limiting actions tend to prevent the formation of an arc and tend to extinguish quickly an arc that may be formed. The blocks chill the metal vapors and smother the arc. The oil tamps the fuse and the pressure created by the arc explosion forces the oil in upon the arc to extinguish the same. On alternating current the pressure of the oil easily extinguishes the arc when the current value passes through zero to reverse as it does at each half cycle.

It is apparent that the oil may be maintained constantly under pressure or may be otherwise made to exert a pressure for extinguishing the arc or for maintaining the arc within the range of operation of the compression blocks. Other insulating liquids than oil may be used and I employ the term "oil" herein as one example of suitable liquids.

My invention aims further to provide improved structural features which are pointed out more particularly in the appended claims.

In order to acquaint those skilled in the art with the manner of making and prac-

tising the invention, I shall now describe in detail a specific embodiment of the invention.

In the accompanying drawings which 5 form a part of the specification—

Figure 1 is a top plan view of the cut-out and hanger with certain parts broken away for the sake of clearness;

Fig. 2 is a side elevation of the same;

10 Fig. 3 is a front elevation of the lug on the lid of the casing shown in Figs. 1 and 2;

Fig. 4 is a fragmentary sectional view of the casing showing the nipples for leading in the connecting cables;

15 Fig. 5 is a side elevation of the movable cut-out element showing the handle, the shield, the compression block, fuse and contacts;

Fig. 6 is an elevation of the stationary 20 element of the cut-out showing the base block of insulation and the stationary contact element;

Fig. 7 is a plan view of the blank from 25 which the stationary contact is manufactured;

Fig. 8 is a plan view of the fuse;

Fig. 9 is a side elevation of the detachable compression blocks showing the spring catches;

30 Figs. 10 and 11 are different forms of vents for the casings for relieving excessive pressure;

Fig. 12 is a fragmentary cross section 35 through the casing, the base block, the compression blocks and the fuse;

Fig. 13 is a horizontal cross sectional view generally on line 13—13 of Fig. 14; and

Fig. 14 is a vertical cross sectional view 40 of a modified form of casing, showing the inner parts in plan and elevation, respectively.

Figs. 1 and 2 illustrate the preferred form of casing and hanger.

The working parts within the casing are 45 the same throughout the figures.

The fuse 1 which comprises a small flat strip of soft metal, such as an alloy of tin and zinc or aluminum and some other metal, is connected at its ends to the movable or 50 plunger contacts 2 and 3 by means of the screws 4 and the clips 5. The opposite flat faces of the fuse 1 are engaged by the lime-stone blocks 6 and 7 which are mounted upon the removable backing block 8 and the 55 carrier or plunger block 9, respectively.

Flint or quartz may be used instead of lime-stone for the blocks 6 and 7. The contacts 2 and 3 which are carried on the edges of the plunger or carrier block 9 are stamped 60 out of sheet metal and are provided with arms 10 and 11 suitably notched to receive the co-operating spring catches 12 and 13. The spring catches 12 and 13 are pivotally mounted upon the backing block 8. Pins 65 14 limit the movement of the spring catches

12 and 13 which press the backing block 8 and the carrier block 9 together, thus compressing the fuse between the compression blocks 6 and 7. The carrier or plunger 9 extends upwardly and is provided with a 70 suitable U-shaped handle 15 by which the block 9 is manipulated. The handle 15 has its legs 16 extending down along the edges of the block 9 to which these legs are secured.

75 A circular disk 17 forms a shield for the hand of the operator, this shield being secured to the top of the block 9 as by means of the angle brackets 18 and 19. The movable contacts 2 and 3 which are mounted 80 on the plunger 9 are adapted to engage with the stationary contact brackets 22 and 23.

The stationary contact brackets 22 and 23 have their shorter legs secured to the base block 25 at the under surface thereof and 85 the longer legs 26 and 27 extend through slots 28 and 29 in the base member 25 and have their upper ends clamped under the binding posts 30 and 31. These stationary contact brackets 22 and 23 are of a general 90 U-shape, with the contact members 20 arranged at the bottom of the U.

Fig. 7 shows the blank stamped out of sheet metal for constructing the contact bracket with the contact attached. The contact 95 20 is formed of a pair of lugs 33 and 34 projecting from opposite edges of the bottom of the U, these lugs are slit as is shown at 35 and 36 to increase the flexibility so that a larger area of contact is secured. 100

A pair of small lugs 37—38 project from the side edges of the lug 33 and these small lugs are bent around the edges of the lug 34 when the lug 34 is bent up into parallelism with the lug 33. They are adapted to prevent accidental bending of the lug 34 out of its proper position. They also insure entry of the movable contacts 2—3 centrally of the corresponding contacts 22 and 23.

The ends of the legs of the U-shaped 110 blanks are bent at right angles as indicated on the dotted lines 40 and 41. This permits motion of the stationary contacts 22 and 23 with respect to each other to a sufficient extent to accommodate themselves to the movable contacts 2 and 3 thus insuring easy insertion and removal of the carrier or plunger 9. The shape of the bracket is such as to brace the contact in the other direction and thus insure the requisite permanency. 115

120 In addition to serving as a supporting base for the relatively stationary contacts 22 and 23, the base block 25 performs the very important function of limiting the movement of the compression blocks 6 and 7. The center of the base block 25 is suitably apertured to receive the plunger or carrier 9 and the backing block 8. At the back of the plunger 9 the base block 25 approaches very closely, being separated only 125 130

by the small gap 42 which is ample clearance for the insertion of the carrier element and its connected parts.

Clearance is provided along the edges of the carrier block 9 as is shown by the spaces 43 and 44 (see Fig. 13). Suitable clearance is also provided as shown by the portions 45 and 46 for the projecting detent arms 10-11 and the spring catches 12-13. The backing block 8 is separated at its center from the base block 25 for a small clearance 47 which limits lateral movement of the backing block and the corresponding compression block. The ends of the compression block 8 lie very close to the base block 25 being separated only by the small clearances 48 and 49. As a consequence the movement of the compression blocks 6 and 7 is limited by the encircling base block 25. It is apparent that separate means may be employed for limiting the movement of the compression block but I find that the arrangement indicated is ideal because of the fact that these surfaces which limit movement of the compression block also serve as guides during insertion of the plunger member, as well as supporting the stationary contacts 22 and 23.

The base block 25 is provided with a circumferential groove 50 and in this groove I provide a winding of piano wire 51 serving as a hoop to reinforce the base block 25 against the bursting effort of the blocks 8 and 9 when they are forced outwardly. A split ring 52 is laid in the groove 51 and this ring is secured to the casing 53 as by means of screws 54. It is apparent that the block 25 may be mounted in the casing as by means of bayonet slots and pins or other known means. The incoming conductors 55 and 56 (see Fig. 13) are connected to the binding posts 30 and 31 as by means of set screws 57. To prevent accidental connection being made between these binding posts I provide a shield or barrier 58 of insulation between these binding posts and the aperture in the base block 25. Thus it is impossible to make contact between the projecting lugs 11 and the binding posts 30-31 by incorrect insertion of the plunger 9. This barrier 58 is supported from the base block 25 as by means of the angle brackets 60 and screws 60'. These screws are shown in section in Fig. 13 the barrier 58 and brackets 55 being removed for the sake of clearness.

In Figs. 1 and 2 I have shown the preferred form of casing for inclosing the working parts. This casing consists of a pot or bowl shaped casing 61 having a drain plug 62 in the bottom thereof. The upper edge of the pot is provided with a flange 63 which co-operates with the flange of the lid 64. Suitable leading-in nipples 65 and 66 are arranged in line with each other near the rear of the shell 61. These nipples are

shown in section in Fig. 4. They are provided with internal grooves 67. A suitable insulating thimble having corrugated outer surface is inserted from the outside into the opening in the nipple and wax or cement is poured in between the corrugations of the insulating sleeve and the grooves 67 thus holding the parts firmly in place. Suitable supporting lugs 68 and 69 are formed integral with the casing or shell 61 and the nipples 65-66, these lugs being perforated and adapted to be slipped over the pins 70-71 on a separate supporting bracket 72. The supporting bracket 72 is adapted to be fastened in place on a cross arm or on a switchboard panel or the like and the cut-out casing is then mounted upon the bracket by slipping the lugs 68 and 69 over the pins 70-71 and resting the body of the casing 61 against the extending prop or support 73 which holds the lower part of the casing 61 in the correct position. Cotter pins 74 are passed through the ends of the pins 70-71 and thus the cut-out is firmly hung in position. The lid 64 is provided with strengthening ribs 75 which extend to the rear of the device and are loosely hinged to suitable hinge brackets 76 as may be seen in Figs. 1 and 2. The cover 64 is clamped down upon the top of the casing 61 by means of a pair of claws 77 and 78, these claws having suitably shaped hooks at their extremities as is shown at 79 in Fig. 2, so that as the claws 77 and 78 are drawn together by means of the screw bolts 80 and threaded handle 81 they cause the lid to be firmly wedged down upon the flange 63.

The screw bolt 80 is provided with a square head 82 having a rounded under surface 83 which permits the bolt to center itself with respect to the claws 77. The square head 82 prevents turning of the bolt when the handle 81 is turned. The bolt 80 passes through a central lug 84 formed on top of the lid 64 and suitable coil springs 85 and 86 are interposed between this lug 84 and the claws 77 and 78. These springs push the claws outward when the handle 81 is turned to release the bolt. The lug 84 is provided with a pin 87 which forms a suitable eye for raising the lid 64.

The casing 61 is provided with a vent or safety valve 88 which releases when the pressure within the casing 61 becomes too great. This vent is illustrated in Fig. 11 and consists of a casing 89 having a valve seat 90 normally closed by a ball valve 91. The ball valve 91 is normally pressed on its seat by means of the spring 92. The spring 92 is pressed down by the cap 93 which closes the end of the valve casing 89. When the pressure within the casing becomes excessive the ball valve 91 is lifted from its seat and pressure is released by way of the ports 94, 95.

In Fig. 10 I have shown a modified form of vent. The nipple 96 at its inner end communicates with the inside of the casing 61 and at its outside end is closed by a membrane or diaphragm 97 held on the end of the nipple by means of an aperture cap 98. Excessive pressure blows out the membrane or diaphragm 97 thus affording release. The membrane 97 may be made of such a thickness that it will yield and thus give an indication of the blowing of the fuse. This, however, is not always desirable.

The casing or shell illustrated in Figs. 13 and 14 is provided with a lid 100 held down upon the flanges 101 by means of the bolts 102 and wing nuts 103. It is understood in each case that a suitable gasket is placed between the lid and the corresponding flange. The lid 100 is provided with a handle 104. The casing 53 is suspended upon bracket arms 105 formed integral with the walls of the casing. These bracket arms are slotted as shown at 106 in Fig. 14 so that the bolts which are to support the device may first be fastened in place and then the brackets hooked over the bolts 107 by means of the slots 106.

In Figs. 13 and 15 I have indicated the manner in which an overhead cable 108 may be led into the casing 53 as shown at the right of these figures. The casing 53 is provided with hollow lug or boss 109 having a suitable opening for receiving the porcelain bushing 110. After the conductor 56 is secured in place the bushing 110 and the hollow boss 109 are closed off by means of the cement or wax 111. The bushing 110 may be made of any suitable insulating material. At the left of Figs. 13 and 14 I have illustrated a manner in which lead covered cables such as are used underground may be led into the casing 53 of the cut-out device. For this purpose the hollow lug or boss 112 is threaded as shown at 113 to receive the wiping sleeve 114, which sleeve is then united to the lead sleeve 115 of the cable, as by means of the wiped joint 116 shown in Fig. 14. The different ways of leading in the conductors or cables may be varied as desired, the above instances showing the adaptability of the construction for any particular use.

The operation of the device is as follows: Assuming that the casing 61 or 53 is properly mounted and that the conductors are connected to the binding posts, the interior of the casing is substantially filled with oil or other suitable insulating liquid to about the broken line indicated at 117 in Fig. 14. This body of oil is sufficient to cover the binding posts, the stationary and movable contacts, the fuse and the compression block. The plunger member with the connected parts is then inserted in place so that the contacts 2 and 3, between which

the fuse 1 is connected, are in proper electrical contact with the stationary contacts 22 and 23. It is to be noted that the stationary contacts 22 and 23 are in effect sockets and the upper edges of the lugs 70 which form these sockets are bent outwardly so as to aid in properly alining the stationary and movable contacts. The cover or lid is then put in place and clamped down to render the casing substantially fluid tight. 75 The space between the upper surface of the insulating liquid and the cover or lid is preferably relatively small so that the pressure will rise rapidly when the fuse blows, as will be set out later. Assume that the 80 current passing through the fuse 1 rises to an overload value. The oil has very restricted contact with the fuse 1 being in contact only with the edge of the same, consequently there is practically no circulation 85 of the oil set up. The heat that is generated is therefore retained substantially in the fuse and the immediately adjacent part. Such heat as escapes through the compression block and the backing block moves 90 very slowly due to the poor conductivity of these parts. Consequently the rate in rise of the overload does not appreciably affect the rating of the fuse as is the case in the usual oil submerged fuse. When the over-load current melts the fuse 1, the springs 12 and 13 push the backing block 8 and the compression block 6 in to choke out and damp the arc which tends to form. At the same time the oil is squeezed out from between the blocks 6 and 7 but it prevents the escape of any vapors which might tend to reestablish the flow of current if the oil were not present.

In the case of violent overload in the nature of short circuits, the real ability of the device is displayed. The fuse 1 is vaporized due to the sudden generation of heat with substantially an explosive effect. The backing block 8 strikes against the base block 25 110 on one side and the plunger block 9 strikes against the base block on the other side, thus limiting the space within which the arc is formed. The escape of any vapors from the space between the compression blocks 6 and 115 7 serves to raise the pressure within the casing thereby tending to force the oil into the space between the blocks to extinguish the arc. The movement of the compression block is limited mechanically and the movement of the oil is limited by the liquid pressure so that the greater the tendency to generate vapor so much greater will be the tendency of the oil to press in and extinguish the arc. Further—the tendency for an arc 125 to maintain itself is discouraged due to the well known phenomena of the snuffing out tendency of high fluid pressures on electric arcs.

The motion limiting action which the base 130

block 25 performs prevents damage to the springs 12, 13.

When the fuse 1 has blown the carrier block 9 may be removed by opening the lid 5 of the casing and pulling upward on the handle 15.

The springs 12, 13 are then disconnected from the detent arms 10 and 11 and the backing block 8 with the attached compression block 6 is then released so that a new 10 fuse may be put in place.

The plunger or carrier is then inserted again into the opening in the base block 25 and is guided by the base block so that the 15 relatively movable contacts 2 and 3 engage the relatively stationary contacts 22 and 23 again closing the circuit.

I do not intend that the invention shall be limited to the precise details of construction shown and described.

I claim:

1. In combination a fuse, compression blocks lying on opposite sides of the fuse, means pressing the compression blocks toward each other, a movable carrier member, contacts mounted on said carrier member, said contacts being electrically connected to said fuse, means for limiting the motion of the compression blocks away from 25 each other and relatively stationary contact members mounted on said motion limiting means.

2. In combination, a base member, stationary contacts mounted on said member, a 35 movable carrier element having contacts for engaging said stationary contacts, a fuse connecting the relatively movable contacts, compression blocks on opposite sides of the fuse, means pressing said blocks against the 40 sides of the fuse, said base member having means for limiting the movement of the compression blocks away from each other.

3. In combination, a base block having an aperture therethrough, relatively stationary 45 contacts mounted on the lower side of said base block, a plunger member adapted to be inserted through said aperture, said plunger carrying plunger contacts for engaging the relatively stationary contacts, a fuse connecting said plunger contacts, compression blocks on opposite sides of the fuse, spring 50 means for urging the compression blocks toward each other, the walls of the aperture in said base blocks being so formed as to 55 guide the plunger contacts into position and to limit the outward movement of the compression blocks with respect to each other.

4. In combination a casing, a base block 60 of insulation secured on the inside of said casing, relatively stationary contacts secured to said base block on the lower side of the same, said base block having an aperture therethrough, a plunger member adapted to enter said aperture, said plunger member 65 having plunger contacts for engaging said

relatively stationary contacts, a fuse between said plunger contacts, compression blocks on opposite sides of the fuse and means to press said blocks against said fuse, said base block having means to limit said 70 compression blocks in their movement with respect to each other.

5. In combination, a base block having an aperture therethrough, a U-shaped bracket mounted on the lower side of said base 75 block, a plunger, a contact on said plunger, a fuse on said plunger, compression blocks for said fuse, the wall of said aperture serving to limit the outward movement of said compression blocks, and serving as a guide 80 for the plunger.

6. In combination, a base block having an aperture therethrough, a U-shaped contact bracket adjacent each side of the aperture upon the lower surface of said block, a carrier block having contacts at the sides thereof adapted to coöperate with said U-shaped contact brackets, a fuse connected between the contacts on said carrier block and wires connected to said U-shaped contact brackets, the aperture in said base block serving as a guide for said carrier block, when the contacts are brought into engagement with the contact brackets.

7. In combination, a carrier block having 95 contacts on the edges thereof, said contacts extending down below said block, detent arms extending from the side edges of the contacts, a compression block mounted on said carrier block transversely thereof, a 100 backing block having spring means for engaging the detent arms, said backing block having a compression block parallel with the first compression block, and a fuse connecting said contacts, said fuse lying between 105 the compression blocks.

8. In combination, an apertured base block, a pair of U-shaped contact brackets, one of the legs of each bracket lying in a narrow slot, binding posts mounted on the 110 upper surface of the base block and connecting with the corresponding legs of the U-shaped contact brackets, said contact brackets having contacts forming sockets adjacent the edges of the aperture, and a 115 plunger member guided by said aperture, said plunger member having contacts thereon connected by a fuse and engaging said contacts on the contact brackets.

9. A contact bracket comprising a flat U- 120 shaped stamping of metal, having lugs projecting on opposite sides at the bottom of the U, said lugs being bent into parallelism and forming a contact socket, and the end of one leg of the U being bent at substantially 125 right angles to form attaching means.

10. In combination, a base block having an aperture therethrough, relatively stationary contacts upon the one side of the base block adjacent the edges of the aperture, a 130

- plunger adapted to be guided by said aperture, said plunger having plunger contacts adapted to engage the relatively stationary contacts, a fuse connecting said plunger contacts, binding posts on said base block and a barrier of insulating material between the binding posts and the aperture.
11. In combination, a plunger block, a U-shaped handle, a disk forming a hand shield, said disk being apertured and angle brackets between the U-shaped handle and the disk, the legs of the U-shaped handle passing through the disk and being secured to the plunger block.
- 15 12. In combination a fuse, a pair of compression blocks lying on each side of said fuse, means for forcing the compression blocks toward each other, means for limiting the movement of the compression blocks away from each other, a body of oil inclosing said fuse and said compression blocks, and a substantially fluid tight casing inclosing the body of oil.
13. In combination, a fuse, a compression block lying on one side of said fuse, a block lying on the other side of said fuse, means

for forcing said blocks toward each other, contacts secured to one of said blocks, a handle connected to one of said blocks, means for limiting the movement of said blocks away from each other and stationary contact means mounted on said motion limiting means.

14. In combination a base member, stationary contacts mounted on said member, a movable carrier element having contacts for engaging said stationary contacts, a fuse collecting the relatively movable contacts, compression blocks on opposite sides of the fuse, means pressing said blocks against the sides of the fuse, said base blocks having means for limiting the movement of the compression blocks away from each other, a casing inclosing the above named elements, and a body of oil in which said elements are submerged which body of oil substantially fills said casing.

In witness whereof, I hereunto subscribe my name this 7th day of August, A. D. 1917.

ALFRED HERZ.

It is hereby certified that in Letters Patent No. 1,380,556, granted June 7, 1921, upon the application of Alfred Herz, of Chicago, Illinois, for an improvement in "Fused Cut-Outs," errors appear in the printed specification requiring correction as follows: Page 5, line 53, claim 3, for "tward" read *toward*; page 6, line 38, claim 14, for the word "collecting" read *connecting*; and that the said Letters Patent should be read with these corrections therein that the same may conform to the record of the case in the Patent Office.

Signed and sealed this 28th day of June, A. D., 1921.

[SEAL.]

KARL FENNING,
Acting Commissioner of Patents.

Cl. 200—129.
